SIGNALING APPARATUS

Clarence E. Lomax, Oak Park, and Arthur Bessey Smith, Evanston, Ill., assignors to Associated Electric Laboratories, Inc., Chicago, Ill., a corporation of Delaware

Application April 27, 1939, Serial No. 270,390

10 Claims. (Cl. 179—16)

The present invention relates to signaling apparatus and, more particularly, to improvements in connecting links of the character utilized in establishing connections between the lines of a signaling or telephone system.

It is an object of the invention to provide a connecting link of the character indicated wherein the line connecting apparatus is arranged in an improved manner to be controlled by an element which is exceedingly fast in its response to voltage changes and is substantially non-conductive.

It is another object of the invention to provide an impulse repeating link arranged in an improved manner to include a pulsing device of nonmagnetic character which possesses great sensitivity to voltage pulses.

It is a further object of the invention to provide a line selecting switch adapted for use in a signaling or telephone system which comprises impulse responsive line selecting means arranged in an improved manner to include a pulsing device of nonmagnetic character which is characterized by great sensitivity to voltage pulses.

In general, the objects as set forth above are attained in accordance with the present invention by providing in a signaling system, a connecting link which comprises apparatus for forwarding a connection routed to the link, and circuit means comprising a crystalline body formed of Rochelle salt or equivalent material for controlling the call forwarding apparatus. Two embodiments of the line connecting link are disclosed, one thereof comprising an impulse responsive selector switch of the character used in automatic telephone systems and the other comprising an impulse repeater of the general type conventionally associated with heavily loaded rural lines terminating at a small rural community telephone exchange. In each of the two embodiments of the invention there is provided a pulsing device in the form of a body supported to permit movement of at least a portion thereof, together with pulsing contacts, operative in response to movement of the body, for repeating, to an associated pulsing circuit, impulses transmitted to the link. This body is formed of crystalline material and, in the preferred embodiment, is comprised of Rochelle salt. When properly constructed and shaped, the body is movable in response to changes in voltage impressed between predetermined points thereof. The body as thus constructed is essentially a voltage responsive device, it being substantially nonconductive and being exceedingly fast in its response to changes in the

voltage impressed between the above-mentioned predetermined points thereof.

Further features of the invention pertain to the particular arrangement of the circuit elements whereby the pulsing devices of the respective embodiments of the invention are controlled and additional operating features are attained.

The novel features believed to be characteristic of the invention are set forth with particularity in the appended claims. The invention, both as to its organization and method of operation together with further objects and advantages thereof, will best be understood by reference to the specification taken in connection with the accompanying drawing, the single figure of which illustrates the invention in its embodiment in an automatic telephone system.

In general, the system illustrated in the drawing comprises a relatively small community automatic exchange which terminates a plurality of subscribers' lines, two of which are indicated at 10 and 11 as extending to the substations A and B, respectively. Although the line 11 is illustrated as having only one substation associated therewith, this line may be of the multiparty type having a plurality of substations associated therewith, the apparatus provided at each of the other substations being arranged in the same general manner as that provided at the substation B. In order to establish connections between the lines, there is provided in the exchange automatic switching apparatus which includes a pair of line switches 12 and 13 individual to the lines 10 and 11, a selector switch 14 and a connector switch 15. The substation A associated with the line 10 is of the well-known common battery type of which several commercial embodiments are available. The substation B, on the other hand, is of the local battery type. In the interests of simplifying the disclosure, only that portion of the apparatus provided at the substation B which is required in order to explain the operation of the invention has been illustrated in the drawing. In brief, the apparatus provided at the substation B comprises a transmitter 20, a receiver 21, an induction coil 22 and a local battery 23; which circuit elements are arranged to be interconnected by means of a hook switch 24 which includes a switchhook 34 for supporting the receiver 21 when not in use. The substation further comprises a pulsing or calling device, of the well-known dial operated type, which includes pulsing springs 25 for transmitting switching control impulses over the line 11. In order to indicate the presence of incoming

calls on the line 11, there is also provided at the substation B a signal device in the form of a ringer 26 which includes windings 27 and 28 normally bridged across the line conductors 11a and 11b in series with a condenser 29.

Each of the line switches embodied in the automatic switching apparatus provided in the exchange is preferably of the well-known rotary type. The intermediate selector switches are preferably of the well-known Strowger type. The final selector or connector switches of the exchange are all of identical arrangement. In brief, the connector switch 15 comprises a plurality of bank contacts arranged in levels and terminating the conductors of certain of the subscribers' lines; a wiper carriage structure including the wipers 166 to 168, inclusive; means comprising a vertical magnet 124 for elevating the wiper carriage structure to bring the wipers opposite a desired level of contacts; means comprising a rotary magnet 157 for rotating the indicated wipers until they engage a desired set of contacts in a selected level; a release magnet 118; two sets of off-normal springs 108 and 119; and a plurality of control relays constructed and arranged in the manner illustrated. More particularly, the control relays of the connector switch 15 include a back-bridge relay R100, a line relay R110, a pair of slow-to-release hold relays R115 and R120, a slow-to-release digit transfer relay R125, a slow-acting ring cut-off relay R130, a busy test relay R135, a slow-to-release pulse responsive relay R140 and a slow-to-operate line switching relay R150. The control apparatus of the connector switch further comprises a pulsing device which includes an elongated piezo-electric, crystalline body 160, preferably formed of Rochelle salt crystal. This body is fixedly mounted at points adjacent one end thereof upon a suitable base structure 161. More particularly, the body 160 is constructed and connected in circuit in the manner disclosed in Patent No. 1,802,782, Sawyer, granted April 28, 1931. The elongated body 160, when constructed of material of the character described, is substantially nonconductive and is characterized by the property of movement of the free end thereof in response to changes in the voltage impressed across predetermined points thereof. Movement of the free end of the body 160 is transmitted through an insulating button 164 to an armature 165 which controls pulsing contacts included in pulsing circuits traced hereinafter for respectively energizing the vertical and rotary magnets 124 and 157. The arrangement of the circuit elements is such that the voltage of the exchange battery 117 is normally impressed between predetermined points or surfaces of the crystalline body 160 over a circuit which serially includes the windings of the line relay R110, and a pair of electrodes 162 and 163 adhesively secured to opposite surfaces of the body 160. The electrodes 162 and 163 are bonded or otherwise secured to the surfaces of the body 160 which are substantially perpendicular to the minor axis of the body. As thus connected, the voltage impressed between the electrodes causes the free end of the body to be bent slightly upward, thereby to maintain the armature 165 in engagement with its associated upper contact.

The connector switch 15 may further comprise code selecting apparatus which is impulse responsive and is operative to select the coded ringing currents corresponding to desired sub-

stations associated with the multiparty lines of the system. Since this apparatus may be of conventional construction and the arrangement thereof forms no part of the present invention, it has not been illustrated in the drawing.

In order to repeat to the automatic line selecting switches of the exchange impulses transmitted over the line 11 from one of the substations associated with this line, there is associated with the line an impulse repeating link 16. This link comprises a repeating coil 200 and three control relays R210, R220 and R230, the first and second of which are of the slow-to-release type. The relay R230 is of the alternating current type and includes a winding normally bridged between the link line conductors C169 and C170 in series with a condenser 232. The relays R210 and R230 are provided for the purpose of controlling the transmission of ringing current over the line 11. The link further comprises a pulsing device which is identical in construction with the pulsing device described above and embodied in the connector switch 15. More particularly, the pulsing device of the link 16 comprises an elongated piezo-electric crystalline body 213, preferably formed of Rochelle salt crystal, which is supported upon a base structure 214 and includes a movable free end, the movement of which is transmitted to a pair of contact spring control armatures 218 and 219 through an insulating button 217. For the purpose of impressing the voltage of the exchange battery 117 between predetermined points of the body 213, there are provided two electrodes 215 and 216 which are adhesively secured to the surfaces of the body which are substantially parallel to the major axis of the body.

Referring now to the operation of the system and considering first a call initiated at the substation A and intended for the substation B, the call is initiated in the usual manner by removal of the receiver provided at the substation A from its associated supporting hook or cradle, whereby a loop circuit including the two sides of the line 10 is completed between the substation A and the line switch 12. The line switch 12 responds to the completion of this loop circuit by operating to select a trunk line extending to an idle one of the selector switches to which it has access. Assuming that the selector switch 14, for example, is the first available idle switch accessible to the line switch 12, when the trunk line extending to the selector switch is tested and found to be idle, the line switch 12 operates to extend the calling loop circuit by way of the selected trunk line to the selector switch 14. In response to this operation, the control apparatus of the selector switch 14 is conditioned to respond to the impulses of the first digit of the directory number designating the desired substation B and the usual dial tone signal is returned over the calling loop circuit to indicate to the calling party that the dialing operation may be started. In response to the impulses of the first digit dialed at the calling substation, the wipers of the selector switch 14 are elevated to a position opposite the level of band contacts terminating the trunk lines extending to the group of connector switches including the switch 15. When this first digit is dialed, the control apparatus of the selector switch 14 also operates to terminate the dial tone signal. During the interdigit pause between the first and second digits, the wipers of the selector switch 14 are automatically rotated in a well-known manner

successively to test the condition of the trunk lines terminating in the selected contact level. Assuming, for example, that the connector switch 15 is the first available idle switch of the selected group, when the trunk line extending to this connector switch is tested by the selector switch 14 and found to be idle, the calling loop circuit is switched through to the indicated connector switch. When the calling loop circuit is extended to the connector switch 15, a relatively low resistance short-circuiting path comprising the calling loop circuit is completed for effectively short-circuiting the electrodes 162 and 163 of the pulsing device comprising the crystalline body 160. This path may be traced as extending from the electrode 162 by way of RA102, the upper side of the loop extending to the substation A, the bridge across the conductors of the line 10 at the substation A, the lower side of the calling loop circuit and RA104 to the electrode 163. By virtue of the completion of this path, the magnitude of the voltage impressed between the electrodes 162 and 163 is determined by the resistance of the calling loop circuit. This voltage is decreased below the voltage of the exchange battery 117 by an amount equal to the voltage drop across the windings of the line relay R110. Due to the decreased voltage between the electrodes 162 and 163, the free end of the body 160 is caused to move downward to actuate the armature 165 out of engagement with its associated upper contact and into engagement with its associated lower contact, thereby to prepare a circuit for energizing the slow-to-release relay R120. When the windings of the line relay R110 are energized over the calling loop circuit, the line relay operates to complete, at RA111, an obvious circuit for energizing the slow-to-release relay R115. The relay R115, upon operating, completes the above-mentioned circuit for energizing the slow-to-release relay R120, this circuit extending from ground by way of RA116, the armature 165 and its associated lower contact and the winding of R120 to battery. The relay R120, upon operating, prepares, at RA123, a circuit, traced hereinafter, for energizing the relay R125 in series with the vertical magnet 124. At RA122, the relay R120 completes an obvious path for impressing ground potential upon the release conductor C106. At RA121, the relay R120 connects the control conductor C107 of the trunk line incoming to the connector switch 15 to ground, thereby to complete circuits, not shown, for maintaining the selector switch 14 and the line switch 12 operated. Following the operation of the relay R120, the connector switch 15 is conditioned to respond to the impulses of the second digit of the directory number designating the desired substation B.

During the impulses of the second and third digits dialed at the calling substation, the above-traced low resistance path shunting the electrodes 162 and 163 is intermittently opened and closed. The number of times this path is interrupted during a digit is, in each instance, determined by the numerical value of the digit. For example, if the second and third digits of the directory number designating the desired substation B are five and six, respectively, the above-traced path will be interrupted five times during the second digit and six times during the third digit. Each time this path is interrupted the relay R110 is deenergized and restores, and the full voltage of the exchange battery 117 is impressed across the electrodes 162 and 163. As

5 a result, the free end of the body 160 is deflected upward so that the armature 165 is moved out of engagement with its associated lower contact and into engagement with its associated upper contact. Thus, the pulsing contacts associated with the armature 165 are closed during the open circuit portion of each impulse and are disengaged during the closed circuit period of each impulse. The impulses of the second digit are, by virtue of the above-described operation of the pulsing device, repeated to the vertical magnet 124 over a circuit which first extends from ground by way of RA116, the armature 165 and its associated upper contact, RA123, the off-normal springs 128 and 127, the winding of R125 and the winding of the magnet 124 to battery. In response to the intermittent operation of the magnet 124, the wipers 166 to 168, inclusive, are stepped vertically to a position opposite the level of bank contacts terminating the link line extending to the repeater 16. At the beginning of the first impulse when the relay R125 is first energized, this relay operates to prepare, at RA126, an alternative pulsing circuit including its own winding and the winding of the vertical magnet 124. This alternative pulsing circuit is completed when the wipers 166 to 168 are moved one step in the vertical direction, at which time the off-normal springs 128 and 129 are closed and the off-normal springs 127 and 128 are disengaged. Specifically, this alternative circuit extends from ground by way of RA116, the armature 165 and its associated upper contact, RA123, the off-normal springs 128 and 129, RA126, the winding of R125 and the winding of the magnet 124 to battery. Due to the slow-to-release characteristics of the relays R115, R120 and R125, all of these relays remain operated during the impulses of the second digit. The off-normal springs 119 are closed to prepare a circuit for energizing the release magnet 118 in response to the first vertical step taken by the wipers 166 to 168, inclusive. Shortly following the end of the second digit and during the interdigit pause between the second and third digits, the relay R125 restores RA126 to open a point in the above-traced alternative pulsing circuit and to prepare a circuit for energizing the relay R140 in parallel with the rotary magnet 157. This latter circuit is completed each time the pulsing device operates during the impulses of the third digit and may be traced as extending from ground by way of RA116, the armature 165 and its associated upper contact, RA123, the off-normal springs 128 and 129, and RA126 to RA137 where it divides; one branch extending through the winding of R140 to battery and the other branch extending by way of RA155 and the winding of the magnet 157 to battery. The relay R140, upon operating in response to the initial completion of this circuit, prepares, at RA141 and RA142, a test circuit including the winding of the busy test relay R135. At RA143, the relay R140 completes a path in multiple with the armature RA137, thereby to prevent the impulsing circuit extending through the winding of the rotary magnet 157 from being interrupted through operation of the busy relay R135 as the wipers 166 to 168, inclusive, are moved over contacts terminating the conductors of busy lines. Due to the slow-to-release characteristics thereof, the relays R115, R120 and R140 all remain operated throughout the third series of impulses. At the end of the last impulse of the third digit the wipers 166 to 168, inclusive, are moved into engagement with the

conductors terminating the link line extending to the repeater 16, and this line is tested to determine the idle or busy condition thereof. Assuming the called line to be busy at the time it is selected, the busy test relay is energized over the above-mentioned test circuit, which circuit extends by way of the grounded private conductor of the link line extending to the repeater 16, the wiper 167, RA141, RA142 and the winding of R135 to battery. Upon operating, the relay R135 opens, at RA131, a point in the initially traced circuit for energizing the relay R140 and the rotary magnet 157 in parallel. At RA136, the relay R135 opens a point in the circuit traced hereinafter for energizing the line switching relay R150 and prepares a holding circuit for itself. This holding circuit is completed in response to the release of the relay R140 shortly following the end of the third digit and may be traced as extending from ground by way of RA121, C107, RA136, RA142 and the winding of R135 to battery. At RA138, the relay R135 completes a path for conducting busy tone current by way of the calling loop circuit for the purpose of signaling the calling party that the desired connection cannot be obtained. This path may partially be traced as extending from one terminal of the busy tone source, not shown, by way of C158, the condenser 159 and RA138 to the lower side of the calling loop circuit. Following the operation of the busy test relay R135 in the manner just explained, no further operation of the apparatus occurs until the connection is cleared out at the calling substation. The manner in which the switch train is released when the calling subscriber replaces the receiver provided at the substation A upon its supporting hook or cradle is explained hereinafter.

Assuming the called line 11 to be idle at the time it is selected, battery potential is present upon the private or control conductor of the link line extending to the repeater 16 so that the busy test relay R135 is not energized over the previously traced test circuit. Shortly following the selection of the line, the relay R140 restores in the manner pointed out above. Upon restoring, this relay completes, at RA141, the above-mentioned circuit for energizing the slow-to-operate line switching relay R150, this circuit extending from ground by way of RA121, RA136, the lower winding of R150, RA141, and the wiper 167 to the negative battery terminal as connected to the private conductor of the link line extending to the repeater 16 through the windings of the cut-off relay conventionally embodied in the line switch 13. When its lower winding is energized over this circuit, the relay R150 first completes at the "X" contacts associated with RA154 a holding circuit for itself, this holding circuit extending by way of the grounded release conductor C106, RA154 and the upper winding of R150 to battery. Thereafter the relay R150 opens, at RA155, a point in the previously traced circuit for energizing the rotary magnet 157 and completes, at RA153, an obvious path for impressing ground potential upon the private conductor of the link line extending to the repeater 16, thereby to mark the line 11 as busy in the bank contacts of the other connector switches having access to this line. At RA152 and RA156, the relay R150 completes a circuit for projecting ringing current over the link line extending to the repeater 16, thereby to energize the relay R230. This circuit may be traced as extending from one terminal of the ringing current source, not

shown, by way of the interrupting contacts of the ringing interrupter embodied in the exchange, the lower winding of R130, RA131, RA152, the wiper 166, C169, the condenser 232, the winding of R230, RA221, C170, the wiper 168, RA156, RA133, and the exchange battery to the opposite terminal of the ringing current source. This circuit is intermittently completed through operation of the ringing interrupter. Each time the alternating current relay R230 is energized by current traversing this circuit it operates to complete, at RA231, an obvious circuit for energizing the slow-to-release relay R210. The relay R210, in turn, operates its armatures RA211 and RA212, thereby to connect the line conductors 11a and 11b to the conductors C169 and C170. In response to the last-mentioned operation, a portion of the ringing current is shunted by way of the conductors of the line 11 through the windings 27 and 28 of the ringer 26 and the condenser 29. Accordingly, the ringer 26 is caused to operate to produce an audible signal indicating the presence of a call upon the line 11. The relay R150, upon operating, also completes, at RA151, a path including the condenser 144 for shunting a portion of the ringing current by way of the calling loop circuit, whereby the usual ring-back tone signal is produced through operation of the receiver provided at the calling substation.

In order to answer the call at the substation B, the receiver 21 is removed from the switchhook 34. In response to this operation the hook switch 24 is operated to move the springs 30, 31, 32 and 33 respectively into engagement. At the contact springs 30 an obvious local loop circuit, including the battery 23, is completed for energizing the transmitter 20, thereby to render this transmitter operative to transmit voice frequency currents over the line 11. At the contact springs 31 and 32 the receiver 21 is bridged across the conductors of the line 11, thereby to render this receiver operative to reproduce signal currents incoming to the substation B. At the springs 32 and 33 a simplex circuit is completed for impressing the voltage of the exchange battery 117 between the electrodes 215 and 216 of the pulsing device included in the repeater 16. Thus, the negative terminal of the exchange battery 117 is normally connected to the lower electrode 216 and, when the hook switch 24 is operated, the positive or grounded terminal of the battery 117 is connected to the upper electrode 215 over a path extending by way of the pulsing springs 25, the contact springs 33, the winding 27, the conductor 11a, RA211 and the winding 201 to the electrode 215. A parallel path extends from ground by way of the pulsing springs 25, the contact springs 33, the winding 28, the contact springs 32, the conductor 11b, RA212 and the winding 202 to the electrode 215. When the voltage of the current source 111 is thus impressed between the electrodes 215 and 216 the stress developed in the body 213 causes the free end of this body to be deflected downwardly, so that the contact springs associated with the armature 218 are closed and the contact springs associated with the armature 219 are moved into engagement. At the contacts associated with the armature 218, an obvious circuit is completed for energizing the slow-to-release relay R200, causing this relay to operate and disconnect, at RA221, the winding of the relay R230 from across the line conductors C169 and C170. Thus, the relays R230 and R210 are caused se-

quentially to restore in the order named. At the contacts associated with the armature 219 a loop circuit is completed for energizing the lower winding of the ring cut-off relay R130. This loop circuit extends from ground by way of RA133, RA156, the wiper 168, C170, the armature 219, the winding 204, the resistor 205, the winding 203, C169, the wiper 166, RA152, RA131 and the lower winding of R130 to the negative terminal of the exchange battery. When this direct current circuit is completed the relay R130 operates to complete, at the "X" contacts associated with RA132, an obvious circuit for energizing its upper winding. Thereafter, the relay R130 completes its operation to open, at RA131 and RA133, two points in the above-traced circuit for projecting ringing current over the link line extending to the repeater 16 and two points in its own operating circuit. At RA131, the relay R130 also opens a point in the above-traced path 20 for conducting a portion of the ringing current by way of the calling loop circuit, thereby to terminate the ring-back tone signal. At RA131 and RA133 and their respective associated working contacts, the relay R130 completes the desired conversational circuit between the calling and called substations and in so doing completes a circuit for energizing the back-bridge relay R100. The last-mentioned circuit extends from ground through the lower winding of R100 by 30 way of RA133, RA156, the wiper 168, C170, the armature 219, the winding 204, the resistor 205, the winding 203, C169, the wiper 166, RA152, RA131 and the upper winding of R100 to battery. When energized over this loop circuit, the relay 35 R100 operates its armatures RA102 to RA105, inclusive, to reverse the direction of current flow over the calling loop circuit in the usual manner. At RA101, the relay R100 completes an obvious multiple path for impressing ground potential 40 upon the release conductor C106.

The arrangement of the connector switch 15 is such that the release of a switch train including this switch is entirely under the control of the calling party. Thus, following the completion of the connection between the calling substation A and the called substation B, if the called party replaces the receiver 21 upon the switch-hook 34 the above traced circuit for impressing the voltage of the source 117 between the electrodes 215 and 216 is interrupted, so that the body 213 assumes its normal position and the armatures 218 and 219 are operated to open the loop circuit extending through the winding of the back-bridge relay R100 and to open the operating circuit for the slow-to-release relay R220. At the hook switch springs 30, the previously described local loop circuit including the battery 23 is interrupted. At the springs 31 and 32, the receiver 21 is disconnected from across the conductors of the line 11. The relay R220, upon restoring, reconnects the winding of the alternating current relay R230 across the line conductors C169 and C170. The back-bridge relay R100, upon restoring, reverses the direction of current flow over the calling loop circuit and at RA101 disconnects multiple ground from the release conductor C106. When the call is cleared out at the calling substation, the previously traced low resistance path shunting the electrodes 162 and 163 is interrupted with the result that the line relay R110 restores and the free end of the crystalline body 160 is deflected upward to open at the armature 165 the operating circuit for the relay R120. Accordingly, the 70

5 relays R110, R115 and R120 are caused to restore in an obvious manner. Upon restoring, the relay R115 completes, at RA116, the previously mentioned circuit for energizing the release magnet 118, causing the wipers 166 to 168, inclusive, to be returned to vertical and rotary normal in a manner well understood in the art. When these wipers are restored to their respective normal positions the off-normal springs 119 are disengaged to open the operating circuit for the release magnet 118. The relay R120, upon restoring, disconnects the control conductor C107 and the release conductor C106 from ground, thereby to initiate the release of the selector switch 13 and the line switch 12 and to cause the restoration of the operated relays R130 and R150. During the release of the connector switch, ground potential is removed from the private conductor of the link line extending to the repeater 16, thereby to mark the line 11 as idle in the bank contacts of the connector switches having access thereto. Ground potential is similarly removed from the private conductor of the calling line 10 during the release of the operated switches 15, 14 and 12. Thus, the apparatus utilized in setting up the connection is fully released.

The release of the switches 12, 14 and 15 is effected in the exact manner described above when the calling party at the substation A is the first to hang up, it being pointed out that the back-bridge relay R100 is deenergized and restores in response to operation of the release magnet and when the wipers 166 to 168, inclusive, are moved out of engagement with the contacts terminating the conductors of the link line extending to the repeater 16. In the event the called line 11 is busy at the time it is selected by the connector switch 15, the release of the switch train is effected when the calling party hangs up. In response to this operation the calling loop circuit is interrupted to cause the reoperation of the pulsing device including the body 160 and the sequential restoration of the relays R110, R115 and R120. The busy test relay is released in response to the restoration of the hold relay R120. Otherwise, the switch train is released in the manner previously described.

50 Referring now to the operation of the apparatus to establish a connection between the substations B and A on a call originating at the substation B, the call is initiated by removing the receiver 21 from its supporting hook 34. In response to this operation, the springs 30, 31, 32 and 33 are respectively moved into engagement. At the springs 32 and 33, the previously traced circuit is completed for impressing the voltage of the exchange battery 117 between the electrodes 215 and 216. As a result, the free end of the body 213 is deflected downwardly to complete the previously traced circuit for energizing the slow-to-release relay R220. Upon operation, the relay R220 disconnects, at its armatures RA221, the winding of the alternating current relay R230 from across the line conductors C169 and C170. At the contact springs associated with the armature 219 a loop circuit is completed which extends from the repeating coil 200 to the line switch 213. This loop circuit may partially be traced as extending by way of C169, the winding 203, the resistor 205, the winding 204, the armature 219 and the conductor C170. In response to the completion of this circuit, the line switch 13 operates to select an idle one of the selector switches to which it has access. Assuming that

the selector switch 14 and the connector switch 15 are utilized in setting up the desired connection, these switches successively respond to the impulses making up the digits of the directory number designating the substation A. Thus, the selector switch 14, as selected by the line switch 13, responds to the impulses of the first digit dialed at the substation B by operating to select the connector switch 15. The last-mentioned switch, in turn, responds to the impulses of the second and third digits by operating to select the called line 10. During the dialing operation the impulses transmitted through operation of the pulsing springs 25 over the line 11 are repeated through operation of the pulsing device in the repeater 16 to the selector and connector switches 14 and 15, respectively. Thus, each time the springs 25 are opened, the above-traced circuit for impressing the voltage of the exchange battery 117 between the electrodes 215 and 216 is interrupted. As a result, the free end of the body 213 is moved upwardly so that the contact springs associated with the armature 219 are opened to interrupt the loop circuit extending from the repeating coil 200 through the line switch 13. The contact springs associated with the armature 218 are also disengaged during each impulse to open the operating circuit for the relay R220, but due to its slow-to-release characteristic, this relay remains operated during impulsion. Aside from the manner in which the impulses are repeated to the switches 14 and 15, the connection is routed to the substation A in the exact manner set forth above with reference to the call routed to the substation B. Furthermore, the release of the connection is effected in substantially the manner described above when the calling party replaces the receiver 21 upon its supporting hook 34. In response to this operation, the hook switch springs 32 and 33 are disengaged to open the circuit for impressing the voltage of the exchange battery 117 between the electrodes 215 and 216. Accordingly, the body 213 assumes its normal position to open, at the armatures 218 and 219, the operating circuit for the relay R220 and the loop circuit extending to the connector switch 15, thereby to initiate the release of the switches 15, 14 and 13. When the relay R220 restores, the apparatus embodied in the repeater 16 is fully released.

While there have been described what are at present considered to be the preferred embodiments of the invention, it will be understood that various modifications may be made therein, and it is intended to cover in the appended claims all such modifications as fall within the true spirit and scope of the invention.

What is claimed is:

1. In a signaling system, a connecting link adapted for use in establishing connections between the lines of the system and comprising, in combination, a body supported to permit movement of at least a portion thereof, means for impressing a voltage between predetermined points of said body, means for shunting said predetermined points of said body, thereby to change the voltage across said predetermined points, said body being comprised of a material such that a portion of said body moves in response to changes in the voltage impressed between said predetermined points, and apparatus comprising circuit means controlled in accordance with the movement of said body for forwarding a connection routed by way of said link.

2. In a signaling system, a connecting link 75

adapted for use in establishing connections between the lines of the system and comprising, in combination, a body supported at points adjacent one end thereof and having a free end, means for impressing a voltage between predetermined points of said body, means for shunting said predetermined points of said body, thereby to change the voltage across said predetermined points, said body being comprised of a material such that the free end of said body changes its position in response to changes in the voltage impressed between said predetermined points, and apparatus comprising circuit means controlled in accordance with changes in the position of said body for forwarding a connection routed by way of said link.

3. In a signaling system, a connecting link adapted for use in a connection extending between two lines of the system and comprising, in combination, a pulsing device comprising a body supported to permit movement of at least a portion thereof, means for impressing a voltage between predetermined points of said body, means comprising a pulsing circuit for intermittently shunting said points, thereby intermittently to change said voltage, said body being comprised of a material such that a portion of said body moves in response to changes in the voltage impressed between said predetermined points, pulsing contacts operative in response to movement of said body, and a pulsing circuit controlled by said contacts.

4. In a signaling system, a connecting link adapted for use in establishing connections between the lines of the system and comprising, in combination, a source of voltage, a line relay comprising a pair of windings, circuit means controlled by said relay, a pulsing device comprising a body supported to permit movement of at least a portion thereof, a circuit serially including said windings, said source and said body, whereby the voltage of said source is normally impressed between predetermined points of said body, means comprising a pulsing circuit for intermittently shunting said device, thereby to cause the intermittent operation of said relay and intermittently to change the voltage between said predetermined points of said body, said body being comprised of a material such that a portion of said body moves in response to changes in the voltage impressed between said predetermined points, pulsing contacts operative in response to movement of said body, and a pulsing circuit controlled by said contacts.

5. In a signaling system, a connecting link adapted for use in establishing connections between the lines of the system and comprising, in combination, a source of voltage, an impedance element providing direct current paths and comprising a pair of windings for blocking the flow of audio frequency currents over said paths, a pulsing device comprising a body supported to permit movement of at least a portion thereof, a circuit serially including said windings, said source and said body, whereby the voltage of said source is normally impressed between predetermined points of said body, means comprising a pulsing circuit for intermittently shunting said device, thereby to cause the intermittent operation of said relay and intermittently to change the voltage between said predetermined points of said body, said body being comprised of a material such that a portion of said body moves in response to changes in the voltage impressed between said predetermined points, pulsing contacts operative in response to movement of said body, and a pulsing circuit controlled by said contacts.

tacts operative in response to movement of said contacts, and a pulsing circuit controlled by said contacts.

6. In a signaling system, a connecting link adapted for use in establishing connections between the lines of the system and comprising, in combination, a source of voltage, an impedance element providing direct current paths and comprising a pair of windings for blocking the flow of audio frequency currents over said paths, a pulsing device comprising a body of Rochelle salt supported to permit movement of at least a portion thereof, a circuit serially including said windings, said source and said body, whereby the voltage of said source is normally impressed between predetermined points of said body, means comprising a pulsing circuit for intermittently shunting said device, thereby to cause the intermittent operation of said relay and intermittently to change the voltage between said predetermined points of said body, said body being comprised of a material such that a portion of said body moves in response to changes in the voltage impressed between said predetermined points, pulsing contacts operative in response to movement of said contacts, and a pulsing circuit controlled by said contacts.

7. In a signaling system, a selector switch having a trunk line incoming thereto and comprising pulse responsive line selecting means, a pulsing device comprising a body supported to permit movement of at least a portion thereof, a source of direct current, an impedance element for conducting current from said source to said trunk line and including a pair of windings for blocking the flow of audio frequency currents through said source, a circuit serially including said source, said body and said windings, whereby the voltage of said source is normally impressed between predetermined points of said body, means comprising a pulsing circuit extending by way of said trunk line for intermittently shunting said predetermined points of said body, thereby intermittently to change the voltage between said predetermined points, said body being comprised of a material such that at least a portion of said body moves in response to a change in the voltage between said predetermined points, pulsing contacts operative in response to movement of said body, and a pulsing circuit including said contacts for controlling said line selecting means.

8. In a signaling system, a selector switch having a trunk line incoming thereto and comprising pulse responsive line selecting means, a pulsing device comprising a body of Rochelle salt supported to permit movement of at least a portion thereof, a source of direct current, an impedance element for conducting current from said source to said trunk line and including a pair of windings for blocking the flow of audio frequency currents through said source, a circuit serially including said source, said body and said windings, whereby the voltage of said source is normally

impressed between predetermined points of said body, means comprising a pulsing circuit extending by way of said trunk line for intermittently shunting said predetermined points, thereby intermittently to change the voltage between said predetermined points, at least a portion of said body being movable in response to a change in the voltage between said predetermined points, pulsing contacts operative in response to movement of said body, and a pulsing circuit including said contacts for controlling said line selecting means.

9. In a signaling system, a selector switch having a trunk line incoming thereto and comprising pulse responsive line selecting means, a pulsing device comprising a body supported to permit movement of at least a portion thereof, a source of direct current, a line relay including a pair of windings providing paths for conducting current from said source to said trunk line, a slow-to-release hold relay controlled by said line relay, a circuit serially including said source, said body and said windings, whereby the voltage of said source is normally impressed between predetermined points of said body, means comprising a pulsing circuit extending by way of said trunk line for intermittently shunting said predetermined points, thereby to cause the intermittent operation of said line relay and intermittently to change the voltage between said predetermined points, said body being comprised of a material such that at least a portion of said body moves in response to a change in the voltage between said predetermined points, pulsing contacts operative in response to movement of said body, and a pulsing circuit including said contacts for controlling said line selecting means.

10. In a signaling system, a selector switch having a trunk line incoming thereto and comprising pulse responsive line selecting means, a pulsing device comprising a body of Rochelle salt supported to permit movement of at least a portion thereof, a source of direct current, a line relay including a pair of windings providing paths for conducting current from said source to said trunk line, a slow-to-release hold relay controlled by said line relay, a circuit serially including said source, said body and said windings, whereby the voltage of said source is normally impressed between predetermined points of said body, means comprising a pulsing circuit extending by way of said trunk line for intermittently shunting said predetermined points, thereby to cause the intermittent operation of said line relay and intermittently to change the voltage between said predetermined points, at least a portion of said body being movable in response to a change in the voltage between said predetermined points, pulsing contacts operative in response to movement of said body, and a pulsing circuit including said contacts for controlling said line selecting means.
